UNITED STATES PATENT OFFICE

2,646,993

CLIP BOARD FOR HOLDING WRITING PAPER

John Schwer, Pittsburgh, Pa.

Application June 24, 1952, Serial No. 295,270

2 Claims. (Cl. 281—1)

1

My invention relates to clip boards and the like for holding writing paper, scratch pads, etc., and has for its object the provision of a holder that can conveniently have one corner inserted into the triangular pockets usually employed on desk blotter holders for receiving the corners of desk blotters.

The invention is particularly useful for holding scratch sheets or the like against displacement while writing thereon, when the user's other hand is holding a telephone receiver.

As shown in the accompanying drawing,

Figure 1 is a fragmentary plan view of a desk blotter holder showing the manner in which my invention may be employed therewith;

Fig. 2 is an edge elevational view of the structure of Fig. 1;

Fig. 3 is a view taken on the line III—III of Fig. 1, and

Fig. 4 is a plan view of the base board or plate portion of my invention.

The holder can conveniently be made of sheet metal or a plastic, and comprises a base plate 6 having lips 7 at its edges and bendable downwardly for engagement with the board portion 8 of a desk blotter holder, to prevent the clip board from shifting on the blotter holder when the nose portion 9 of the plate 6 is inserted in one of the triangular pockets formed by the usual leather-like pieces 10 used at the corners of the holder 8 and into which the corners of the blotters are inserted.

Ears 12 are struck up from the plate 6 to serve as bearings for a shaft 13 that also extends through ears 14 struck downwardly from a clamping plate 15. A coil spring 16 surrounds the shaft 13 and has one free end thereof abutting the upper surface of the plate 6, and at its other end, tension against the underface of the clamping plate 15, to thereby exert torsional stress to hold the down-turned edge of the clamping plate in gripping engagement with a sheet of paper or pad 17. If the plate 6 is made of metal, it may suitably have a sheet 18 of cloth glued to the undersurface thereof.

The clamping plate 15 has a lever-like extension 19 by which it can be rocked against the tension of the spring 16 to lift the forward or jaw portion of the plate from the sheets 17.

It will be seen that by reason of the triangular pocket 10 and the lips 7, the plate 6 is held in all directions against shifting. Also, it

2

can readily be removed simply by lifting the outer edge thereof to bring the lips clear of the edges of the holder 8 and sliding the plate away from the corner. In some cases, I may prefer to omit the lips 7.

I claim as my invention:

1. A clip board comprising a base plate, a clamping plate pivotally mounted thereon, on a diagonal axis adjacent to a corner of the base plate, a spring yieldably urging the inner edge of the clamping plate into gripping engagement with sheets that overlie an inner portion of the base plate, and down-turned lips at the marginal edges of the plate, set inwardly from the said corner, the said outer corner being adapted to be slid into a triangular pocket in a desk blotter holder and the lips engageable with the adjacent edges of said holder, at points removed from the triangular pocket.

2. A clip board comprising a base plate having ears struck upwardly therefrom along a diagonal line set inwardly from a corner of the plate, a shaft supported by said ears, with its axis along said diagonal line, a clamping plate supported by said shaft, a spring engageable with the base plate and the clamping plate and biased in a direction to effect gripping engagement between the inner edge of the clamping plate and the adjacent underlying area of the base plate, the said corner being adapted to be slid into a triangular pocket of a desk blotter holder and the said shaft being set inwardly from the diagonal edge of said pocket, so that the outer portion of the clamping plate will be above the pocket can serve as a lever-like extension for opening the inner edge of the clamping plate relative to the base plate.

JOHN SCHWER.
